COMBINED SAFETY RAZOR AND
SHARPENING DEVICELouis V. Aronson, Newark, N. J., assignor to Art
Metal Works, Inc., a corporation of New
Jersey

Application July 24, 1931, Serial No. 552,843

12 Claims. (Cl. 30—12)

This invention relates to improvements in combined safety razors and sharpening devices.

The features of this invention include certain improvements to the type of razors disclosed in

Letters Patent of the United States No. 1,826,410 granted me October 6, 1931. In this type of razor a sharpening device such as an abradant roller or other means which may be conveniently operated by the hand, is attached to the head of the razor and is intended to form a permanent part of the device and a double edged blade is so mounted on the device, that either of the two blade edges may be brought into contact with the razor guard for shaving or with the sharpening device, without removing the blade from its clamping means.

Among the objects of this invention are the provision of improved means for moving the razor blade into a position in which it may be turned about its longitudinal axis, as well as about an axis at right angles to its plane, provision of improved means for holding the razor blade in a position outside of the razor head for facilitating cleaning and replacement of blades and reversal of the position of the blade, improved means for aligning the razor blade with respect to the razor head, and various other improved features in the razor head construction.

Various further and also various more specific objects, features and advantages will more clearly appear from the detailed description given below taken in connection with the accompanying drawing which forms a part of this specification.

The invention consists in such novel features, arrangements and combinations of parts as may be shown, described and claimed in connection with the embodiment of the invention herein disclosed by way of example.

In the drawing—

Fig. 1 is a view of the combined razor and sharpening device as viewed in a direction toward the end of the razor blade;

Fig. 2 is a cross-section of the combined safety razor and sharpening device taken substantially centrally transversely of the razor blade and sharpening device;

Fig. 3 shows the razor blade mounting means moved through an angle of 90° for the purpose of cleaning and replacement of blades and reversal of the position of the blade;

Fig. 4 is a top plan view of the device as shown in Fig. 3;

Fig. 5 is a side view of the device as shown in Fig. 1 and as viewed in a direction toward the right, with portions broken away;

Fig. 6 shows a portion of the device as of Fig. 3 but viewed from the left; and

Fig. 7 is a sectional view taken along the line 7—7 of Fig. 2.

My improved razor includes a razor head generally designated at 10 which may be formed of a piece of sheet metal having material punched out as indicated at 11, Figs. 5 and 2, to decrease its weight and to provide openings facilitating cleaning with water. The razor head 10 may be of a general box-like formation including the side member 12 on which guard fingers are formed, several of which as indicated at 13 may be raised above the level of the others for the purpose of holding the razor blade 14 spaced from the remaining guard teeth.

The razor head also includes a side member 15 and end members 16 and 17 upon which roller supporting ears 18 and 19 are formed, the end members 16 and 17 being preferably secured to the side members 12 and 15 by welding or soldering, as indicated in Fig. 4. Rotatably supported in the ears 18 and 19 are screw bolts 20 and 21 which may be threaded into and rotatable with a sharpening roller 22, to support such roller for rotative movement.

The sharpening roller may for example be formed of a plastic composition of any well-known type embodying fine abradant material. The roller may be rotated by rolling the same over the hand of the user, or otherwise as desired. Spring means within the handle as hereinafter described, provide a construction such that the blade is held in uniform yielding contact with the roller for facilitating proper sharpening action throughout the length of the blade when the roller is rotated.

The razor blade 14 is mounted on a clamping plate 23 which, as shown in Figs. 4 and 5, is provided at its ends with lugs 24 and 25 which engage corresponding notches in the razor blade and in another clamping plate 26 which is drawn towards the first or inner clamping plate 23 by means of a screw bolt 27 threaded into the inner clamping plate and provided with a manipulative head 28 bearing against the outer surface of the clamping plate 26, and with a reduced portion rotatably fitted in the clamping plate 26. This bolt is preferably permanently affixed to the finger piece portion 28 as by a forced fit or by welding. By means of this construction the razor blade 14 may be readily mounted on the clamping plate 23 and readily removed therefrom for replacement.

The clamping plate 23 is rotatably supported

by means of short screws 30 and 31 threaded into the enlarged portions 24 and 25 of the clamping plate 23 and bearing freely in the arms 32 and 33 of a U-shaped member generally designated at 5 34, which is vertically slidable in the open box-like razor head 12. This rotatable supporting means permits the razor blade to present its edges in cooperative relation to the guard and sharpening device and permits rotative movement 10 of the blade to move the opposite faces of the edges of the blade for cooperation with the guard and sharpening device.

The base 35 of the U-shaped member 34 is slightly enlarged transversely and is provided centrally with a rectangular hole at 36, as shown in Fig. 7, fitted to a squared end portion 37 of a plunger 38 which extends through the handle 39 on which the razor head 12 is rigidly mounted. The plunger 38 is provided adjacent to the squared 20 end portion 37 with fixed collars 40 and 41 securing the U-shaped member 34 on the end of the plunger 38.

For the purpose of aligning the razor blade supporting means with the guard 13 and the sharpening roller 22, the arms 32 and 33 of the member 25 34 may be provided with studs 42 and 43 which cooperate with slots 44 and 45 in the end walls 16 and 17 of the razor head 12 so that when the razor blade is moved into the position shown in 30 Fig. 2 the edges of the razor blade will be firmly retained in proper relationship with the guard 13 and the sharpening roller 22.

For the purpose of holding the razor blade in the position shown in Fig. 2, and also to permit 35 its supporting and clamping means to be moved outwardly and away from the guard and roller so that it may be turned about its longitudinal axis or bodily about an axis perpendicular thereto to reverse the relation of the blade edge surfaces with respect to the guard and sharpening 40 roller, I provide a spring 46 bearing against a shoulder 47 on the interior of the handle 39 and against a manipulative member 48 carried by the plunger 38. The manipulative portion may be 45 threaded or otherwise engaged with the lower end of the plunger 38 to permit easy assembling or separation of the parts.

As shown in Fig. 2 the razor handle 39 may be 50 provided with an enlargement or collar at 50 formed separately and secured thereto in any desired manner, or which may, if desired, be integral with the handle, the outer edges of the same being preferably milled so that the collar 55 may be held securely during the various operations in using the razor.

The manipulative portion 48 is preferably provided with a somewhat spherical end face and a knurled enlargement as shown, and preferably 60 includes a cylindrical external skirt portion 51 which surrounds and is slidable on the handle 39. By means of this construction, as is apparent from Fig. 3, the index finger and middle finger of one hand may be placed on the collar 50 and the thumb of the same hand may be placed on the rounded end of the manipulative portion 48 to move the plunger upwardly and to raise the razor blade 14 out of cooperative relation with the guard and roller, and into a position in which the razor blade is free to be turned about the axis 65 of the plunger 38. After the razor blade has been moved into this position it may be turned also about its longitudinal axis, or the razor blade together with the U-shaped member 34 and the stem 38 may be rotated by grasping the skirt portion 51 of the manipulative member 48 between

the thumb and index finger of the other hand, the skirt portion 51 being preferably provided with ribs to facilitate rotative movement. The razor blade may thus be turned edge for edge, or into the position shown in Fig. 3 in which position the parts may be readily cleaned.

When the razor blade has been moved into the position shown in Fig. 3, pressure may be removed from the manipulative portion 48 in which case the spring 46 will draw the U-shaped member 34 into contact with the roller 22. For the purpose of preventing accidental rotation of the razor blade out of the position shown in Figs. 3, 4 and 6, two curved portions 52 and 53 may be formed in the base 35 of the member 34 shaped to fit the roller 22. It is evident from Fig. 3 that regardless of the direction in which the plunger 38 and razor blade 14 are turned they will be held in position as indicated in Fig. 3 by the roller 22 and the cooperating portion 52 or 53.

It will be apparent that the box-like construction of the head piece 10 will serve to rigidly support the guard and sharpening roller in proper relationship to the blade, and the walls of the 100 box-like enclosure may be made of relatively thin light weight material and still possess sufficient rigidity to prevent the razor parts from being bent out of proper relationship. It will be noted that in the ordinary use of the razor and the 105 removal of the blade or during insertion of a new blade, it will be merely necessary to release the clamping member 26 by turning the thumb screw 28. The construction of the restricted neck portion of the thumb screw 28 is such that this 110 screw will always remain attached to the clamping plate 26. Accordingly even when the blade is being replaced, the entire razor construction and sharpening device will be constituted of but two parts and accordingly the likelihood of any of 115 the parts being mislaid is obviated. During the replacing of the blade, if the parts are kept in the position shown in Fig. 1, the blade clamping members will be relatively rigidly held in position so that the thumb screw 28 may be readily 120 manipulated without danger to the user. Furthermore, as indicated in Fig. 3 and as above explained, the relative positions of the two blade edges may be reversed while the fingers of both 125 hands are kept in contact with the handle in positions relatively remote from the blade and therefore during the actual use of the razor for shaving, if the blade edge in use becomes dulled somewhat, the user may immediately shift the other blade edge into position without any danger 130 of the parts slipping out of the hands or of the blade edges coming into contact with the fingers.

It will be further noted that the construction of the blade with slots at its ends, contributes substantially to the compact relationship of the 135 parts in that the slotted blade areas provide space for the bearing screws 30 and 31 and their supporting lugs so that such parts need not protrude beyond the outer limits of the adjacent parts of the device.

While the invention has been described in detail with respect to a preferred example thereof which gives satisfactory results, it will be understood by those skilled in the art after understanding the invention, that various changes and modifications may be made without departing from the spirit and scope of the invention and it is intended therefore in the appended claims to cover all such changes and modifications.

- What is claimed as new and desired to be secured by Letters Patent of the United States, is:
1. In a combined safety razor and sharpening device, the combination of a guard member, a sharpening device, means for yieldingly holding the edges of a razor blade under tension against and in operative position with respect to said guard member and sharpening device, means for moving said razor blade away from said guard member and sharpening device and for rotating said razor blade about an axis substantially perpendicular to said blade into a position in which the razor blade is in non-cooperative relation with respect to said guard and sharpening device, and means on said holding means cooperating with said sharpening device under control of said yielding means for holding said razor blade in such rotated position. 80
  2. In a combined safety razor and sharpening device, the combination of a guard member, a sharpening device, means for supporting a razor blade under tension in operative position with respect to said guard member and sharpening device and mounted for moving said blade away from said guard member and sharpening device and for rotation about an axis substantially perpendicular to said blade into a position in which the razor blade is in non-cooperative relation with respect to said guard and sharpening device, and means on said supporting means cooperating with said sharpening device for holding said razor blade in such rotated position. 85
  3. In a combined safety razor and sharpening device, the combination of a guard member, a sharpening device, a razor blade, supporting means mounted for movement to carry the razor blade away from said sharpening device and said guard member and for rotating the blade about an axis substantially perpendicular to the blade, and means on said supporting means conforming to the shape of the sharpening device for cooperation therewith to hold the razor blade in a rotated position. 90
  4. In a combined safety razor and sharpening device, the combination of a guard member, a sharpening device, a razor blade, supporting means mounted for movement to carry the razor blade away from said sharpening device and said guard member and for rotating the blade about an axis substantially perpendicular to the blade, and a plurality of means on said supporting means shaped to conform to the sharpening device to cooperate therewith for holding the razor blade in rotated positions. 100
  5. In a combined safety razor and sharpening device, the combination of a guard member, a sharpening roller, a razor blade, supporting means for yieldingly holding the razor blade against said guard and roller, and means permitting movement of said supporting means to carry the razor blade away from said guard member and roller and to permit rotation of the blade about an axis substantially perpendicular to the blade, said supporting means including a base provided with curved depressed portions either one of which is adapted to cooperate with said roller when said supporting means is drawn in a rotated position against said roller by said yielding means. 105
  6. In a safety razor, the combination of a handle, a substantially open topped box-like razor head secured to said handle and comprising side walls and end walls, a guard member on said head, a substantially yoke-shaped razor blade supporting means adapted for movement into and out of the open top of said box-like head, and cooperating means on the arms of said yoke-shaped supporting means and the ends of said box-like head for aligning an edge of the razor blade with said guard member. 110
  7. In a combined safety razor and sharpening device, the combination of a handle, a razor head of general box-like shape rigidly secured to said handle and comprising end walls and side walls and having its top open, a guard member supported on one side of said head, a sharpening device supported on the other side of said head, a razor blade supporting means movable into and out of the top of box-like head, and cooperating means on the end walls of said box-like head and said razor blade supporting means for aligning the edges of the razor blade with said sharpening device and said guard member. 115
  8. In a combined safety razor and sharpening device, the combination of a handle, a razor head supported on said handle and provided with a guard and a sharpening device, a razor blade supporting means mounted in said head, a plunger carrying said razor blade supporting means and mounted for longitudinal and rotative movement in said handle, a manipulative member secured to said plunger and provided with a skirt portion surrounding and slidably engaging said handle, and spring means cooperating with said handle and said plunger for moving the edges of the razor blade into cooperative relation with the guard and sharpening device and for permitting movement of the edges of the razor blade away from said guard and sharpening device into a position in which the razor blade may be rotated substantially about an axis perpendicular to the blade by a rotative movement of said skirt portion. 120
  9. In a safety razor, the combination of a razor head provided with a guard member, a razor handle secured to said head, a manipulative collar on said handle, a razor blade supporting plunger slidable and rotatable in said handle, a manipulative member secured to the end of said plunger and provided with a finger engaging portion at its end, a skirt portion projecting from said finger engaging portion and surrounding said handle, said skirt portion being provided for rotating said plunger when pressure is applied on said manipulative collar on said handle and said finger engaging portion to hold the razor blade out of cooperative relation with said guard member, and yielding means cooperating with said handle and said plunger for moving said razor blade into cooperative relation with said guard member and for permitting movement of said razor blade away from said guard member. 125
  10. In a safety razor, the combination of a razor blade clamping plate, a second razor blade clamping plate provided with recesses at its ends, projections on the first clamping plate adapted to project into said recesses in the second clamping plate, means for moving said clamping plates relatively toward each other, a supporting member for said first clamping plate, and pivotal means connecting said projections to said supporting member. 130
  11. A safety razor having clamping members for clamping a blade therebetween and adapted for rotation about an axis longitudinally of the blade, in which the razor blade is formed with notches at its ends, into which extend portions of at least one of the blade clamps, the pivots of the pivoting means being set into these portions 135
  - 70
  - 75

tions within the notches so that the ends of the blade extend substantially as far as the pivoting means whereby the pivot offers no substantial obstruction in the use of the razor.

- 5 12. A safety razor comprising a razor blade formed with notches at the ends thereof, a pair of clamping members respectively extending over substantial portions of the blade surface, portions of at least one of the said members
- 10 coming into contact with said notches to rigidly affix the blade in position between the clamping

members, and pivoting means for mounting the blade and its clamping members for rotation about an axis extending longitudinally of the blade, the pivots of said pivoting means extending into and being secured in the said portions within the notches, and whereby the notches provide space for a substantial portion of the pivots obviating any substantial extension of the same beyond the blade ends.
